UNITED STATES PATENT OFFICE.

RICHARD G. MILLER, OF HUNTINGTON, WEST VIRGINIA, ASSIGNOR TO ROBERTS AND SCHAEFER COMPANY, OF CHICAGO, ILLINOIS, A CORPORATION OF ILLINOIS.

PICKING TABLE.

Application filed June 1, 1925. Serial No. 33,956.

My invention relates to a screening and picking device, and particularly to a coal handling device which is adapted to screen and grade coal. One object of my invention is to provide a device of the type described wherein a maximum picking area is provided. Another object is the provision of means for maintaining the material being picked in a layer of maximum extension and minimum depth. Another object is the provision of picking areas of maximum length and maximum accessibility. Other objects will appear from time to time in the course of the specification and claims.

I illustrate my invention more or less diagrammatically in the accompanying drawings, wherein:

Figure 1 is a plan view;

Figure 2 is a vertical longitudinal elevation partly in section;

Figure 3 is a sectional plan view of the picking deck showing the picking wings, the section being taken on the line 3-3 of Figure 2;

Figure 4 is a section on the line 4-4 of Figure 1;

Figure 5 is a section on the line 5-5 of Figure 2;

Figure 6 is a section on the line 6-6 of Figure 2; and

Figure 7 is a section on the line 7-7 of Figure 2.

Like parts are illustrated by like symbols throughout the drawings and specification.

A is any suitable supporting surface or structure upon which is supported the frame A¹ for example by means of the supports A². Mounted upon the frame in any suitable manner are the supporting rollers A³, A⁴.

Resting upon the rollers A³ is the plate or member B of the screen provided for example with the supporting blocks or shoes B¹ adapted to engage and move laterally across the rollers A³.

C is the upper screening and conveying member or level provided with the screening surface C¹ positioned substantially beneath the feeding chute C². Beneath it lies the plate D which at the left of the mecha-

nism is shown in Figure 2 supported upon the rollers A⁴ for example by means of the blocks or shoes D¹. It is broken for example by the screen D² beneath which lies the screen E. The part of the material which passes over the screen D² is deflected

by means of the baffle plates D³ to the outer picking wings D⁴ provided with the terminal go-down plates D⁵. The baffle plates may be fixed, but are herein shown as pivoted to permit adjustment. The material which passes over said picking wings D⁴ is deflected inwardly, after it passes over the go-down plates D⁵ to the centrally disposed conveying plate D⁶.

The baffles D³, as herein set, deflect one half of the material passing over the screen D², and the rest of the material passes on over the conveying plate F which is located at the same height as the picking wings D⁴. The proportion of material deflected may be varied at will. The plate F branches beyond the go-down plates D⁵ by means of the outwardly inclined portions F¹ to the picking wings F² situated at the same level as the picking wings D⁴ but longitudinally spaced therefrom. These picking wings terminate at the go-down plates F³ and the material which passes thereover is deflected by means of the side plates F⁴ to the conveying plate D⁶, or B there re-joining the material picked on the screen D², or the material being conveyed along the bottom plate B.

The screen E terminates in a closed portion E¹, and a go-down plate E² which does not quite contact the bottom plate B, may, if desired, be used.

The conveying surface D⁶ may terminate in a downwardly turned portion D⁷ which, if desired, may also be spaced somewhat above the bottom plate B. The bottom plate B in turn terminates in a downwardly turned portion or spout B³ which overhangs any suitable material depositing means, here illustrated as a conveyor G.

H is any suitable spoils trough branching as at H¹H¹ and reuniting as at H², which may be supported at any convenient position, which serves to receive the material picked.

J is any suitable motive means adapted to operate the link J¹ which serves to impart to the screening assembly as a unit reciprocation of unequal velocity, whereby the material on the screen moves from left to right as shown in the figures.

It will be realized that whereas I have illustrated an operative device and one which has been practically successful that nevertheless I may make wide changes in size, shape, number, relation and disposition of parts without departing from the spirit of my in-

vention. I wish my description and drawings therefore to be taken as in a broad sense illustrative rather than as limiting me to my specific showing.

5 The use and operation of my invention are as follows:

I provide a picking screen wherein the coal to be picked is separated into different grades or sizes by the screen. In the herein 10 described screen the egg and nut are the sizes which are passed over the picking areas, but I do not wish to be limited to this particular use of my screen. The material to be picked passes over the chute C² to the screen 15 C¹. The finer material passes through the screen C¹, to the level D while the lump passes forwardly along the deck C. The egg and nut pass forwardly along the level D over the screen D² the finer material dropping through to the surface E. The egg and nut deck is shown in some detail in Figure 20 3. As the picking screen is given its characteristic feeding movement the stream of egg and nut moves to the right across the 25 screen D² until it meets the baffles D³. These baffles are pivoted or fixed, and, when pivoted, may be swung into the position shown in dotted line in Figure 3, but are preferably positioned as shown, to deflect to the 30 picking wings D⁴ about one-half of the stream passing over the screen D². Thus each wing D⁴ takes approximately one-quarter of the total feed of material across the deck, although its proportion may be 35 varied by adjusting the baffles D³. The remaining portion of the material being fed passes forwardly along the plate F and is deflected by the inclining portions F¹ to the picking wings F². The material passing 40 over the picking wings D⁴ has meanwhile descended the go-down plates D⁵ and has been deflected inwardly to the centrally disposed conveying plate D⁶. The material which flows across the picking wings F² in 45 turn descends the go-down plates F³ and is deflected by the members F⁴ to the same central section D⁶, or to B, all the coal thus returning to a single stream after it has been picked. Meanwhile, however, it has 50 been spread out in a thin layer over no less than four picking wings or portions. Along each picking wing are aligned the operators to pick the impurities from the coal and drop the lumps of shale and the like into the spoils 55 troughs H¹. The coal is spread out thin by being passed over a large area and the individual operators along the picking wings, since they have to pick only one-quarter of the flow of coal, and that spread out thin, 60 have their task much simplified. The result is an easier and a more thorough picking of the coal. The coal when picked is in the present structure returned to a single stream and the picked coal may be delivered with 65 or without the lump and the finer coal, to

any suitable receiving means, for example the conveyor G. Whereas I have described the picking of egg and nut, obviously any size of coal may be picked in like manner, or various different sizes, either mixed or 70 segregated.

I claim:

1. In a reciprocating table, a central material conveying portion extending from end to end of the table, and means for reciprocating it, picking wings associated therewith for movement in unison therewith, and adapted to receive material therefrom, adjustable baffles associated with said wings and adapted to control the entry of material 75 into the wings.

2. In a reciprocating table a material conveying portion, a plurality of laterally spaced picking wings supported upon said table and adapted to receive material therefrom, a plurality of picking wings longitudinally spaced from said first mentioned picking wings and adapted to receive material from the same material conveying member, and means for controlling the relative 85 proportion of the material fed to each of said pairs of picking wings.

3. In a picking table, material supplying means, a reciprocating screen portion adapted to receive such material and to convey it forwardly in response to reciprocation thereof, baffles positioned beyond the screen portion and aligned with the outer edges of the stream of material passing thereacross, picking wings mounted upon said table and 95 adapted to receive the material deflected by said baffles, additional picking wings mounted upon said table and adapted to receive the material passing between said baffles.

4. In a picking table, material supplying 105 means, a reciprocating screen portion adapted to receive such material and to convey it forwardly in response to reciprocation thereof, baffles positioned beyond the screen portion and aligned with the outer edges of 110 the stream of material passing thereacross, picking wings mounted upon said table and adapted to receive the material deflected by said baffles, additional picking wings mounted upon said table and adapted to receive the material passing between said baffles, 115 said two sets of picking wings being longitudinally spaced along the table.

5. In a reciprocating screen, means for supplying material thereto, a material conveying surface upon said screen, baffles aligned with the outer portion of the stream of material passing therealong, picking wings mounted upon said table and adapted to receive the material deflected by the 120 baffles, other picking wings mounted upon said table and adapted to receive the material passing between said baffles.

6. In a reciprocating table, means for supplying material thereto, a material convey- 125

ing surface upon said table, baffles aligned with the outer portions of the stream of material passing therealong, picking wings mounted upon said table and adapted to receive the material deflected by the baffles, other picking wings mounted upon said table and adapted to receive the material passing between said baffles, said sets of picking wings being longitudinally spaced along the 10 table.

7. In a reciprocating table, means for supplying material thereto, a material conveying surface upon said table, baffles aligned with the outer portions of the stream 15 of material passing therealong, picking wings adapted to receive the material deflected by the baffles, other picking wings adapted to receive the material passing between said baffles, said sets of picking wings 20 being longitudinally spaced along the screen, and means for reuniting in one stream the material passing through said various picking wings.

8. In a reciprocating table, means for

supplying material thereto, a material conveying surface upon said table, baffles aligned with the outer portions of the stream of material passing therealong, picking wings adapted to receive the material deflected by the baffles, other picking wings 30 adapted to receive the material passing between said baffles, said sets of picking wings being longitudinally spaced along the screen, and means for reuniting in one stream the material passing through said 35 various picking wings, comprising go-down plates adapted to deliver the material passing over the first of said wings to a level lower than the second of said wings, and go-down plates adapted to deliver the material 40 passing over the second of said wings to the same level as that occupied at that point by the material delivered across the first of said sets of wings.

Signed at Huntington, county of Cabell, 45 and State of W. Va., this 9th day of May, 1925.

RICHARD G. MILLER.
